DEVICE FOR HYPODERMIC INJECTIONS

Paul Kollsman, New York, N. Y.

Application December 20, 1947, Serial No. 792,992

1 Claim. (Cl. 128—218)

1

This invention relates to improvements in syringes for hypodermic or intramuscular injection of medicinal compositions. The invention provides a double purpose syringe which is inexpensive to manufacture and which serves as an ampoule for storing a predetermined volume of a medicinal composition. The composition is discharged from the ampoule-syringe directly into body tissue without previous transfer to a separate syringe or other injection device.

The invention also provides a syringe which is extremely simple to operate, one single manipulation of the syringe being sufficient to apply it to the patient, insert the needle and eject the medicinal composition therefrom. The simple and inexpensive construction proposed by the invention makes it advantageous to discard rather than refill the syringe after discharge of the medicinal composition therefrom.

The invention offers in this connection various structural improvements which make syringes non-refillable whereby unauthorized refilling under non-sterile conditions is guarded against.

These and numerous other features, advantages and objects of the invention will appear more fully from the detailed description which follows accompanied by drawings showing, for the purpose of illustration, preferred embodiments of the invention. The invention also consists in certain new and original features of construction and combination of elements herein-after set forth and claimed. Although the features characteristic of this invention which are believed to be novel will be particularly pointed out in the claim appended hereto, the invention itself, its objects and advantages, and the manner in which it may be carried out may be better understood by referring to the following description taken in connection with the accompanying drawings forming a part of this application in which:

Figure 1 is a cross-sectional view of a syringe embodying the invention, a section being taken on line 1—1 of Figure 2;

Figure 2 is a plan view of the syringe shown in section in Figure 1;

Figure 3 is a side view, partly in section, of a modified form of syringe;

Figure 4 is a section taken on line 4—4 in Figure 3; and

2

Figure 5 is a perspective view of a stop member attachable to the plunger shown in Figure 1.

In the following description and in the claims, various details will be identified by specific names for convenience. The names, however, are intended to be generic in their application. Like reference characters refer to like parts in the several figures of the drawings.

In the drawings accompanying, and forming part of this specification, certain specific disclosure of the invention is made for the purpose of explanation of broader aspects of the invention, but it is understood that the details may be modified in various respects without departure from the principles of the invention and that the invention may be applied to other structures than the ones shown.

The subject matter of this application is related to the subject matter of co-pending applications directed to devices of the general type disclosed herein.

Application Serial No. 792,991, filed December 20, 1947, now Patent No. 2,578,812, dated December 18, 1951, discloses and claims a syringe in which the depth of insertion is automatically controlled and limited, and in which stop means are provided permitting measured partial discharge.

Application Serial No. 792,993, filed December 20, 1947, now Patent No. 2,578,813, dated December 18, 1951, discloses and claims a tubular needle seal for a syringe which prevents contamination of the needle and is blow-off proof in that it will not blow off if the syringe fluid is subjected to a sudden rise in pressure, for example by dropping the syringe.

Application Serial No. 792,994, filed December 20, 1947, now Patent No. 2,578,814, dated December 18, 1951, discloses and claims a syringe having a narrow visible and optically enlarged passage leading to the inner end of the needle to facilitate observation, and expulsion of, gas bubbles in the syringe chamber.

Application Serial No. 792,995, filed December 20, 1947, discloses and claims an improved form of non-creeping plunger seal.

The syringe shown in Figures 1 and 2 comprises a barrel 11 in which a plunger 12 is telescopically movable. The plunger 12 is tightly sealed with respect to the interior surface 13 of the barrel

by a gasket 14 which rests in a groove 15 of the plunger and frictionally engages the interior surface 13 of the barrel 11.

In order to make the syringe unfit for re-use after discharge, the barrel 11 and plunger 12 are preferably made from a thermo-responsive preferably clear synthetic plastic which at ordinary room temperatures is hard and shape retaining and which, upon heating to sterilizing temperatures, of the order of the boiling point of water, becomes plastic and loses its shape or changes its appearance, for example by turning opaque. This property of the plastic material makes the barrel and plunger unfit for use after an attempt to sterilize them by heating. Sterilization of the needle alone is discouraged by making it non-removable.

However, the barrel and plunger may initially be sterilized by the manufacturer or the pharmaceutical laboratory distributing the filled syringes by exposing the parts to an atmosphere of sterilizing gas.

In the illustrated form of syringe, the rear surface 16 of the plunger forms a movable wall of a chamber 17 adapted to contain a charge of medicinal fluid confined between the barrel 11 and the plunger 12.

A hollow injection needle 18, preferably of substantially constant outer diameter, is non-removably mounted in the plunger 12 and communicates with the chamber 17 through a hollow passage 19 extending through the plunger. The needle 18 projects from the front end surface 20 of the plunger a distance d equal to the depth to which the needle is to be inserted into the body tissue.

The front end surface 20 is substantially flat and comprises an area large enough to provide sufficient resistance for ejection of the medicinal composition from the syringe without causing discomfort to the patient by reason of excessive local pressure.

The plunger may be provided with adjustable stop means to permit step-by-step discharge of the contents of the syringe. In the form of syringe shown in Figures 1 and 2, the piston is provided with a plurality of circumferential grooves 21 into which a movable stop 22 fits. The stop 22 is preferably made of plastic sheet material and has a jaw-shaped portion 23 adapted frictionally to engage any of the grooves 21 in the piston. Attachment of the stop 22 limits the freedom of telescoping movement of the piston 12, the end of the preset stroke being reached when the stop abuts the end surface 24 of the barrel.

The plunger 12 is suitably calibrated in terms of volumetric units. This may be done by applying scale numerals 25 to the ridges above the respective grooves for the stop 22. For example, the numeral 1.5 indicates that if the stop 22 is placed in the groove 21 below the numeral 1.5, the volume discharged at the time the stop abuts the barrel 11 is 1.5 volumetric units. This arrangement permits any desired fractional volume to be discharged from the syringe.

Refilling of the syringe is mechanically discouraged by making the plunger 12 of a length l_1 equal to, or slightly less than, the length l_2 of the barrel, measured on the inside so that in fully telescoped position the plunger is completely within the barrel 11 and cannot be removed therefrom by hand for the purpose of refilling. The friction which the gasket 14 provides against the interior surface 13 is sufficient to prevent with-

drawal of the plunger from the barrel by a needle 18.

The syringe shown in Figures 1 and 2 is primarily designed for filling with a medicinal fluid composition at the plant or laboratory of the producer, the volume of the fluid being sufficient for a single injection or a series of injections by operating the syringe in repeater fashion with the aid of the adjustable stop 22 as hereinbefore explained. After initial filling, the syringe is sealed by placing over the end of the needle 18 a sealing plug 28 preferably of rubber or any other suitable material. This plug pressure tightly seals the end of the needle to prevent discharge of the fluid therefrom in the event the syringe is accidentally subjected to telescoping force and to maintain the front end of the syringe sterile.

In sealed condition, the syringe serves as an ampoule and is ready for immediate use by removal of the sealing plug 28 and adjustment of the ring 22, if the syringe is equipped with such a ring.

Small air bubbles accidentally trapped in the chamber 17 during the filling of the syringe may easily be removed by placing the filled syringe in an upright position thus causing the bubbles to rise and collect near the passage 19. Collection of the bubbles is facilitated by the conical shape of the rear surface 16 of the plunger 12 as shown in the drawings. Slight telescoping movement of the plunger 12 with respect to the barrel 11 forces the bubbles out through the passage 19 and the needle 18.

The syringe shown in Figures 1 and 2 is used as follows. After removal of the sealing plug 28 from the injection needle 18, the device is ready for immediate use. It is applied to the body of a patient by grasping it at the barrel 11 which provides a finger grip surface or portion 29. The point of the needle 18 is placed on the patient's skin and pressure is then exerted in the direction of the needle 18 to insert the needle into the body tissue. This force does not cause any discharge from the syringe because in the initial state in which the plunger gasket 14 is stationary with respect to the barrel surface 13 the friction therebetween is relatively great and is equivalent to a multiple of the force required for inserting the needle to its full length.

The needle 18 penetrates the body tissue until the front end surface 20 of the plunger comes to rest on the patient's skin, whereafter the force exerted at the barrel is opposed by an equal pressure exerted by the skin against the front surface 20. This is sufficient to overcome the friction of the gasket 14 and the barrel 11 then moves telescopically over the plunger causing the fluid to be discharged through the passage 19 and the needle 18 into the patient's body tissue. The discharge continues until either the plunger reaches its end position in the barrel or until the adjustable ring 22 engages the front surface 24 of the barrel in the case of partial discharge.

After complete discharge of the fluid from the syringe, the syringe is discarded. The low production price and the difficulty of removal of the plunger from the barrel due to its peculiar construction discourages attempts of re-using it.

Figure 3 illustrates a modified form of syringe comprising a barrel 30 within which a plunger 31 is telescopically movable. The plunger may be made from tubular round stock. It is slotted at 32 and an elastic plug 31' inserted between the slotted plunger portions tends to force the slotted portions apart to provide sufficient frictional

engagement of the plunger with the interior surface 33 of the barrel. The plunger may have an enlarged finger operable grip portion 34 and may be provided with a scale 35 readable against the back surface 36 of the barrel.

A movable seal or membrane 37, preferably separate from the plunger 31 is telescopically movable in the barrel and forms a seal of the fluid chamber 38 against the piston 31.

An injection needle 39 is mounted in the front end 40 of the barrel and extends in the illustrated embodiment with its pointed rear end 41 into the chamber 38 to pierce the center portion 42 of the seal 37 when the seal arrives in its end position. Since the seal 37 is not attached to the plunger, it cannot be removed from the barrel by withdrawal of the plunger. Refilling of the syringe is thus discouraged by the difficulty of removing the seal from the barrel and is further rendered impossible by destruction of the seal once the syringe is fully discharged.

Air or gas bubbles accidentally trapped in the chamber 38 may be removed by placing the syringe in an upright position causing the bubbles to collect at the conical end surface 46 of the chamber 38. Slight movement of the plunger 31 then expels the bubbles through the needle 39. Experience has shown that movable seals or pistons 37 of elastic material have a tendency slightly to creep back at the rim portion after the pressure by the plunger on the seal is released. Such creeping of the seal 37 may cause a small air bubble to be drawn into the chamber through the needle. According to the invention, creeping of the seal 37 is prevented by frictional fit of the plunger 31 within the barrel 30. The elastic plug 31' which forces the slotted ends of the plunger 31 apart and against the wall 33 of the barrel provides sufficient friction to check any creeping of the seal, the frictional force being greater than the elastic force of deformation of the seal 37 at the rim portion tending to move the seal back slightly.

The thin center portion 42 of the seal 37 also aids in preventing air from being drawn into the chamber 38. During discharge of fluid from the chamber 38, the center portion 42 is bulged rearwardly to some extent towards the plunger by reason of the fluid pressure upon it. When the piston 31 comes to rest and the pressure inside the chamber 38 drops, the center portion 42 of the seal returns to its normal position and in doing so tends to force out an additional small volume of fluid sufficient to compensate for any creeping of the seal near its rim portion which would tend to draw fluid into the chamber 38.

The syringe shown in Figure 3 is likewise designed for one-time use to be filled at the laboratory or factory. It may be sealed by an appropriate sealing plug 28 for shipment and storage in sterile condition until the time of its use.

When the syringe of Figure 3 is to be used, the sealing plug 28 is removed from its needle 39 and the front end 40. The syringe is grasped by the finger operable portion 34 of the plunger 41 and is placed on the patient's skin. Pressure exerted on the plunger forces the needle 39 into the body tissue until the front end 40 of the barrel comes to rest on the patient's skin. No fluid is expelled from the syringe during the insertion of the needle since the resistance of the needle to insertion is not sufficient to overcome the friction of the movable seal 37. After the needle 39 is completely inserted into the tissue

of the patient, further movement of the piston 31 is opposed by reaction of the skin against the front end 40 of the barrel. This resistance is sufficient to overcome the frictional resistance of the movable seal 37 and liquid is now forced out through the needle 39. At the end of the stroke, the pointed rear-end 41 of the needle pierces the thin center portion 42 of the seal and automatically renders the syringe unfit for refilling without removal and replacement of parts.

The invention thus provides a syringe which, because of its simplicity, is inexpensive to manufacture by modern mass production methods. The cost of the syringe is so small as to make one-time use and discarding after use more profitable than re-use of the syringe.

Safe re-use of a syringe involves inspection, sterilization and re-filling under sterile conditions. Conditions of sterility are difficult to maintain except at establishments specifically equipped for it, for example, laboratories, hospitals and physicians' offices.

Syringes, according to the present invention, lend themselves admirably to use by the patient himself, who, but for rare exceptions, has no facilities for the cleaning, sterilization and re-filling of syringes, thus opening the doors to dangers of infection. The present invention meets a specific need in providing a syringe which is furnished by a pharmaceutical laboratory ready-filled with a specific volume of medicinal composition ready for immediate use by the patient. The syringe reaches the patient in sterile condition and requires no filling or transfer of medicinal fluid from one receptacle into another. The novel syringe thus permits maintenance of a degree of sterility by the average patient which he was not heretofore able to maintain. The syringes embodying the principles of the invention are practically fool-proof in use. They are also particularly safe to use by reason of the limitation of the depth to which the needle may be inserted into the body tissue whereby the danger of improper injection or injury due to contact of the injection needle with bone structure of the patient is eliminated. Thus, a degree of safety is provided in the self-administration of injections which prior to the invention was not regularly attained.

The invention obviously is not restricted to the particular embodiments herein shown and described. Numerous modifications, additions, omissions, substitutions and other changes may be made without departing from the spirit and the essence of the invention as defined in the appended claim. All such changes will be apparent to persons skilled in the art familiar with the disclosure of the invention and do not involve a departure from the spirit and the teachings of the invention.

What is claimed is:

An injection syringe comprising, in combination, a barrel; means forming a movable wall in said barrel, said means including a plunger telescopically fitting into said barrel and a plug of resilient material for sealing said barrel towards said plunger, whereby a variable volume chamber is formed in said barrel adapted to contain a charge of medicinal fluid; a hollow injection needle mounted on said barrel communicating with said chamber, said needle projecting from the front end surface of said barrel; said plunger having a plug engaging end portion

slotted lengthwise of the plunger; and a resilient member for forcing said slotted end portion apart into frictional contact with the barrel wall.
